UNITED STATES PATENT OFFICE

KENNETH SEBASTIAN SAMUEL SPENCER, OF ILFORD, ENGLAND, ASSIGNOR TO GOMER H. REES, OF LONDON, ENGLAND

ACOUSTIC DEVICE PROVIDED WITH VIBRATILE DIAPHRAGMS

Application filed May 31, 1928, Serial No. 281,988, and in Great Britain June 15, 1927.

This invention relates to loud speakers employing cone diaphragms of the direct acting type.

The distortion of various frequencies of the musical range and blasting are mainly attributed to the nature and arrangement of the diaphragm and although the performance of loud speakers has been very greatly improved within recent years, the best results are obtained only by comparatively expensive means and devices which are often inconveniently large for ordinary purposes.

The object of the present invention is to provide a loud speaker with a diaphragm structure or arrangement which is convenient to use and gives clear undistorted reproduction.

To attain this object use is made of a plurality of conical diaphragms of the direct acting type and of different dimensions or shape, so mounted and actuated that undesired resonant effects are obviated. A convenient arrangement is to have two conical diaphragms of different angularities whose apexes are co-axial, the space between them being unenclosed. If the peripheries of the diaphragms be in approximately the same plane, the loud speaker may be very snugly mounted within the cabinet and if desired the diaphragms may very easily be provided with a peripheral hinge member.

The invention is illustrated in the accompanying drawings in which:

Fig. 1 is a front view of a loud speaker according to the invention,

Fig. 2 is a sectional plan view of the loud speaker of Fig. 1,

Fig. 3 is a sectional side elevation showing schematically a modification in diaphragm structure.

Figs. 4 and 5 show in sectional side elevation further modifications of the diaphragm structure.

The sound producing element comprises a plurality of cone diaphragms 1 and 2, which are of different angularity. They are supported upon a bolt 6 by means of spacers 4 and 5 which may conveniently be made from any light material. The bolt 6 is rigidly secured to an armature 3 of the electromag-

netic drive element 7 which may be of any well known type. In order to adjust the position of the armature with respect to the coils of the driving element, the usual milled nut 8 controlling the tension in spring 9 is provided. The electrical leads to the driving element are coupled as shown to terminals 10 positioned upon a panel 11, secured in the back of the cabinet 12. The peripheries of the diaphragms 1 and 2 extend into engagement with felt pads 20 mounted on the inner side of the front panel 17 of the loud speaker cabinet. It is found preferable to have the peripheries of the diaphragms engaging with slight pressure on the felt pads, since this tends to obviate transverse vibrations which may give rise to blasting or similar effects.

However, quite pleasing reproduction can be obtained even if the peripheries of the diaphragms are perfectly free to vibrate. In this case it is found advisable to turn back the edge of the diaphragms for say half an inch from the periphery as shown in Fig. 4.

In order to regulate the pressure which the diaphragms exert upon the felt pads 20, or to effect the entire removal of such pressure, brackets 15 are secured to the sides of the cabinet and support bolts 13 passing through panel 11. Between the panel 11 and the brackets 15 springs 14 are situated. By adjusting the nuts 13 the positioning of the diaphragms may be readily effected. The front panel of the cabinet is provided with openings 19 through which sound waves may be emitted from the interior of diaphragm 2. The panel has also openings 18 which allow sound waves, generated by diaphragm 1, to have ready access to the outside air. By the arrangement of a chamber between diaphragms 1 and 2 it has been found that undesirable resonant effects are obviated, whilst also the reproduction of frequencies over an extremely broad range is obtained with great faithfulness.

The diaphragms are preferably made of stiff paper in the usual manner, and the preferred arrangement is that shown in Figs. 1 and 2. However, instead of using felt pads 20, the diaphragms may each be provided as shown in Fig. 5 with a peripheral flat por-

tion clamped to the front wall of the cabinet, the peripheral portion being sufficiently flexible to allow the effectual vibration of the diaphragms to take place, but at the same time serving to cut out or prevent the setting up of transverse vibrations or blasting.

The term "conical" is meant to cover not only right circular cones but shapes which are analogous in operation.

10 The schematic representation of Fig. 3 shows a modification in which instead of two, three cone diaphragms are used. The preferred angle of the third cone is clearly shown.

15 In all the arrangements it is preferable that the peripheries of the cones should lie in the same plane, but of course this is not essential since the main advantage is merely one of construction.

20 As shown in Fig. 3 the diaphragms 21, 22 and 23 are supported on a bolt 24 by means of spacers 25. The bolt 24 would be secured to the armature of the driving mechanism.

25 The loud speaker may be mounted in a cabinet by itself, or together with the other desired wireless receiving apparatus.

What is claimed is:

1. In a loud speaker a driving element, a plurality of conical diaphragms of different angularities operatively connected to said driving element, and an opening between the peripheries of said diaphragms.

2. In a loud speaker a driving element, a cone diaphragm operatively connected to said driving element, a second cone diaphragm of different angularity to said first diaphragm also operatively connected to said driving element and with its periphery in substantially the same plane as the periphery of the first said diaphragm and spaced a slight distance therefrom.

3. In a loud speaker a driving element, a plurality of conical diaphragms of different angularities operatively connected to said driving element, a containing cabinet, a wall of said cabinet in proximity to the peripheries of said diaphragm, a space in said wall registering with the opening between said diaphragms, and another opening in said wall.

4. In a loud speaker a driving element, a plurality of cone diaphragms of different angularities operatively connected to said driving element, a containing cabinet, a plurality of resilient annular members carried by a wall of said cabinet, each one of said members being engaged by the periphery of one of said diaphragms, openings in said wall communicating between the outside air and the spaces between the diaphragms.

5. In a loud speaker a driving element, a plurality of conical diaphragms of different angularities operatively connected to said driving element, a containing cabinet, a wall of said cabinet in proximity to the peripheries of said diaphragms and means for ad-

justing the proximity of said peripheries to said wall.

6. In a loud speaker a driving element, a plurality of cone diaphragms of different angularities operatively connected with said driving element, a containing cabinet, a plurality of resilient annular members carried by a wall of said cabinet, each one of said members being engaged by the periphery of one of said diaphragms, openings in said wall communicating between the outside air and the spaces between the diaphragms, and means for adjusting the pressure of engagement of said diaphragms on said resilient members.

7. In a loud speaker a driving element, a plurality of cone diaphragms of different angularities operatively connected with said driving element, a containing cabinet having openings therein, a plurality of supporting members, one disposed between the periphery of each diaphragm and the wall of said cabinet, certain of said openings being situated in said walls between said members.

8. In a loud speaker a driving element, a plurality of coaxial conical diaphragms of different angularities connected together, a containing cabinet, resilient annular pads on a wall of said cabinet, the periphery of one of the diaphragms engaging each of said pads and means for regulating the pressure of this engagement.

9. In a loud speaker a driving element, a plurality of cone diaphragms of different angularities operatively connected to said driving element, a containing cabinet, a wall of said cabinet engaging the peripheries of said diaphragms, a second wall of said cabinet carrying said driving element and means for adjusting the pressure of the diaphragms on the first said wall.

10. In a loud speaker a driving element, a plurality of coaxial diaphragms of different angularities operatively connected to said driving element, an unenclosed space between the peripheries of said diaphragms and means for variably adjusting the pressures on the diaphragms.

KENNETH SEBASTIAN SAMUEL SPENCER.
